UNITED STATES PATENT OFFICE

110,957

DESIGN FOR A LAY FIGURE

Ralph L. Chisholm, Cranston, R. I., assignor to Universal Winding Company, Boston, Mass., a corporation of Massachusetts

Application December 20, 1937, Serial No. 73,758

Term of patent 14 years

To all whom it may concern:

Be it known that I, Ralph L. Chisholm, a citizen of the United States, residing at 61 Strathtmore Road, in the city of Cranston, county of Providence, and State of Rhode Island, have invented a new, original, and ornamental Design for a Lay Figure, of which the following is a specification, reference being had to the accompanying drawing, forming a part thereof.

The drawing is a perspective view of a lay figure embodying the design.

I claim:

The ornamental design for a lay figure, substantially as shown.

RALPH L. CHISHOLM.
